General Machinery Corporation, Hamilton,
Ohio, a corporation of Delaware

Application April 14, 1934, Serial No. 720,515

6 Claims. (Cl. 113—38)

This invention relates to power presses and more particularly to presses for drawing sheet metal or the like.

One object of the invention is the provision of a power press having a work plunger or slide which is so driven as to operate at comparatively low speed during the work forming part of a cycle of operations and at a higher rate of speed during the major portion of the remainder of the cycle. 10 Another object of the invention is the provision of a press for drawing or working metal, having a variable speed electric motor drive for the work forming slide, the speed of the drive being automatically varied at a predetermined time in the cycle of press operations to provide for decreased speed of movement of the slide in the work forming part of a cycle.

Other objects and advantages of the invention will be apparent from the following description, 20 the appended claims and accompanying drawings, in which,—

Fig. 1 is a front elevation of a power press embodying the present invention, a part of the lower portion of the press being omitted;

25 Fig. 2 is a side elevation of the upper part of the press;

Fig. 3 is a diagrammatic showing of the electrical control system;

30 Fig. 4 is a partly diagrammatic view of the controlling switches and their operating cams, and

Fig. 5 is a diagrammatic illustration showing the timing of the various speed changes.

Conventional drawing presses are driven from 35 an operating shaft which rotates at a uniform rate of speed, for example at the rate of about six strokes per minute which has been found to be about the most economical rate. If a higher rate of speed is employed it is found that the 40 number of broken stampings, due largely to high drawing speed, is unduly increased. The breakage can be reduced by lowering the number of strokes per minute, but then the total production in any given time period will also be reduced. In 45 accordance with the present invention, however, the operating shaft by means of which the movable slide is driven, is so operated that the speed of the plunger is materially slower during the drawing part of a cycle of operations in order 50 that a comparatively high number of strokes per minute is attained without correspondingly increasing the speed of the drawing operation itself.

The press may be of any suitable character having a movable slide which carries a die for drawing the work, and may be equipped with the usual

air-pressure controlled slide and have any desired number of mechanically moved slides for serving as blank holding members, forming members, etc. As herein shown the press is provided with a plurality of mechanically operated upper slides 11 and 12 and the mechanically operated lower slide 42 which are moved in timed relationship as more fully set forth in my prior United States Patents Nos. 1,768,503 and 1,967,464.

Referring more particularly to the drawings 10 10 designates generally the frame of the press in which the slides 11 and 12 are mounted for reciprocatory movement so that the slide 11 may descend first and dwell for a period of time while the die carried by the slide 12 is effective in drawing the metal. The slides 11 and 12, as shown, are operated by a system of toggle levers, both having a dwell period by reason of the relative arrangement of the centers of the various operating parts.

20 Rotatably mounted in an upper portion of the press frame is a power driven operating shaft 13. This shaft is rotated by two gears 14 and 15 each of which meshes with a pinion 16 provided at opposite ends of a shaft 18 which also carries a gear 17. The gear 17 meshes with the driving pinion 19 provided on a transverse shaft 20 which is driven from an electric motor 21 through a pinion 22 and gear 23, the latter being fixed to the shaft 20.

25 The two gears 14 and 15 are each provided with an eccentric stud 25 which is connected by an arm 26 to a vertically reciprocatory slide block 27, the two slide blocks, one at either side of the frame, being connected to the four rock shaft extensions 28 as more fully explained in my prior patent and application above referred to. The rock shaft extensions 28 are rigid with the short toggle arms 30 pivotally connected to the toggle links 31 and operating the inner slide 12. The 30 connection between the crank shaft 13 and the blank holding slide 11 is effected through toggle links 32 which are connected to toggle arms rigid with the two rock shafts 33 which are operated from the slide 34 driven by operating means connected to the crank throw 36.

35 During the time the slide 12 is dwelling it may itself serve as a blank holder together with the slide 11 while the work is being operated upon by a die which is mounted for reciprocatory movement in a lower portion of the press. Such lower die may be operated by means of the lower die carrying slide designated generally 42. Slide 42 is guided for vertical movement, its opposite ends being connected to operating rods 48 the 45

upper ends of which are formed as eccentric straps 49 engaged with cylindrical surfaces 48 eccentrically provided adjacent opposite ends of the operating shaft 13.

5 The motor 21 which serves as a driving force for the operating shaft 13 by means of which the various slides are reciprocated in timed relationship is a two-speed electric motor of comparatively high horse power capacity so that the 10 motor can pull the press through its peak loads without requiring the storing of energy in a large flywheel. A flywheel of substantial size would prevent rapidly changing the speed of operation of the press at predetermined points in the cycle 15 of operations, so it is preferred that no flywheel be employed. Mounted on the press frame at a suitable location is a cam shaft 50, operated by a timing sprocket chain 51 from the operating shaft 13 so that the shafts 50 and 13 will move in sync- 20 chronism and at the same speed of rotation. The cam shaft 50 is provided with a number of cams 52 to 57 inclusive as shown in Fig. 4 for the operation of switches 58 to 63 inclusive at proper times in the sequence of press operations. 25

25 The electric motor 21 is provided with a high speed winding connected to the leads 65 of a three-phase power supply and also with a low speed winding connected through the leads 66. Power switches 67 and 68 respectively complete 30 the connection to the power source 69. It will be understood that when the switch 68 is closed, the motor is operated at low speed and when the switch 67 is closed and switch 68 opened the motor will operate at high speed. The high 35 speed of operation is such as to give a desired high speed movement of the press parts for the ineffective portions of a cycle of operations, while the low speed of the motor is suitable to provide a drawing speed that will be slow enough so 40 that there will be a minimum amount of breakage in drawing the metal.

As shown in Fig. 5, the motor is automatically controlled by means of the cams 52 to 57, the switches 58 to 63 and the additional apparatus 45 shown in Fig. 3. The press may be started by the operator and the operating shaft 13 will then be driven at high speed from the point *a* to the point *c* in Fig. 5, point *c* being about 80 degrees from point *a*. From the point *c* to the point *d*, 50 an angle corresponding substantially to the drawing or effective operations on the metal, the shaft moves at low speed. From the point *d* which is about 190 degrees from point *a*, the shaft moves at high speed until it has rotated a total 55 of about 340 degrees up to the point *e*. From the point *e* to the point *f* which is about 350 degrees from point *a* the shaft moves at low speed and at the point *f* the brake is applied so as to stop the shaft when point *a* is again reached.

60 As an example of the essential parts of the motor controlling means, Fig. 3 illustrates diagrammatically the electrical connections that may be employed. The power source 69, as shown, is connected to a small motor 70 which 65 drives a low voltage generator 71. The generator 71 supplies current for the low voltage or controlling system. 72 is a main switch and energizes the low voltage system. 73 and 74 are two manually operated switches adapted to be 70 simultaneously operated by the two hands of the attendant to initiate a cycle of operations. When the switches 73 and 74 are both closed by the attendant, a circuit is completed from the generator 71 through switch 72, across contact 75 75, through a normally closed switch 82, through

switch 63 which is normally closed and through the coils 76 and 77 of the low voltage circuit breakers 78 and 79 respectively. When the circuit breaker coils are thus energized the circuit breaking elements complete their respective circuits, the breaker 79 being provided in a reset circuit 80 and the breaker 78 being arranged to connect one side of the low voltage source to a lead 81. With both switches 73 and 74 closed current may flow from the lead 81 across the closed contacts 83 and across the closed contacts 84 to a winding 85, this winding having an armature which closes the switch 67 of the motor 21 and holds the switch 67 closed as long as the winding 85 is energized. A suitable overload circuit breaker 86 may be employed in series with the winding 85.

When the attendant closes the switches 73 and 74 the motor 21 is thus connected so as to operate at high speed. The operator holds the switches 73 and 74 closed until the crank shaft has moved some distance, up to the point *b* of Fig. 5 for example, at which point the switch 58 is closed by cam 52. When the switch 58 closes a holding circuit through the lead 81 is completed maintaining the coil 85 energized and permitting the operator to remove his hands from the two switches 73 and 74. The closed connection across the switch 58 maintains the motor in operation at high speed until the point *c* is reached after about 80 degrees total travel of the operating shaft 13. At this point the switch 58 is automatically opened by its controlling cam, and switch 60 is closed by cam 54. The switch 60 connects the lead 81 to a winding 90 having an armature which closes the switch 68 of the motor 21 and which holds the switch 68 closed as long as the winding 90 is energized. The switch 58 being opened has deenergized the winding 85 and thus opened the switch 67. The motor will therefore 40 operate at its low speed of movement throughout the drawing part of the cycle of operations, up to the point *d* about 190 degrees displacement from the initial point *a*. At the point *d*, the switch 60 is automatically opened to deenergize the winding 90 and thus open the switch 68 and at the same time the switch 59 is automatically closed so as to again energize the winding 85 and cause the motor to operate at high speed. The motor continues moving at high speed from the point *d* to the point *e* which is about 340 degrees from point *a*. At the point *e* the switch 59 is opened automatically and switch 61 is closed so that the speed of the motor is changed from high speed back to low speed. The motor moves at low speed for about 10 degrees movement of the shaft 13, up to the point *f*, and at the point *f* the switch 58 opens and switch 62 closes. When the switch 62 closes both of the switches 67 and 68 of the motor 21 are open, and a stopping force is applied to the shaft 13 through a suitable brake by means of an armature controlled by a winding 91 which is in series with switch 62. The circuit is completed through the winding 91 through switch 62 and across the contacts 93 which are now closed inasmuch as the operator has previously released his hand from the switch 73 and permitted the return movement of the switch to its position shown in Fig. 3. The press will thus stop automatically after a complete cycle of 65 operations the shaft 13 having moved through a total of 360 degrees and again returned to its starting position *a*.

At the same time switch 62 closes for the application of the brake, the switch 63 also opened 70

automatically by the cam 57, switch 63 remaining open, however, only instantaneously, this switch being provided to deenergize the windings 76 and 77 of the low voltage circuit breakers thus opening the resetting circuit 80 and requiring the operator to again close the switch 73 in order to provide a flow of current to the lead 81. This insures against a second cycle of operation being automatically carried on until the operator again closes the starting switches. To carry out a second cycle of press operation, the operator, therefore, merely again moves the switches 73 and 74 downwardly, thus immediately deenergizing the brake applying coil 91 and starting the press 10 through another cycle. 82 is a switch adapted for manual operation in conjunction with the switch 73 for moving the press parts very small amounts,—that is for inching the press along without requiring a complete cycle of operations before stopping.

It will now be apparent that when the operator so desires, he can start the press in operation, and the motor 21 will be so controlled that most of the noneffective part of a cycle of operation is carried out quickly and at high motor speeds, but during the drawing part of a cycle of operation, the drawing slide is moved comparatively slowly and breakage of the finished work is thus avoided.

30 While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A press comprising a frame, a blank holding slide and a drawing slide reciprocably mounted therein, a rotatable shaft, an operating connection between said shaft and blank holding slide and an operating connection between said shaft and said drawing slide producing one complete cycle of slide movements for each revolution of said shaft, means for driving said shaft at high speed and at low speed, and means operable in timed relation to said shaft for decreasing its speed of operation substantially for the extent of the work forming part of a cycle of press operations.

2. A press for forming metal sheets comprising a frame, a die carrying slide reciprocably mounted therein, an operating shaft operable at high speed and at low speed, a connection between said shaft and said slide producing one complete cycle of slide movements for each revolution of said shaft, drive means for operating said shaft at high and low speeds, and means operable in timed relation with said shaft for

causing low speed movements during the work forming part of a cycle of press operations.

3. A press for forming metal sheets comprising a frame, a die carrying slide reciprocably mounted therein, an operating shaft operable at high speed and at low speed, a mechanical connection between said shaft and said slide, a variable speed electric motor drive for operating said shaft at high speed and low speed, and means synchronized with said operating shaft to vary the speed of said drive at a predetermined time in the cycle of press operations to provide for decreased speed of movement of the slide in the work forming part of a cycle of operations.

4. A drawing press comprising a frame, a metal drawing slide reciprocably mounted therein, an operating shaft operable at high speed and at low speed, a connection between said shaft and said slide, a variable speed electric motor for operating said shaft at high speed and low speed, timing means movable in timed relation with said shaft, and a switch system controlled by said timing means and controlling the motor speed, said timing means and switch means providing for low speed operation of said slide during the drawing part of a cycle of operations and providing for high speed operation of said slide throughout the major part of the non-drawing part of a cycle of operations.

5. A press comprising a frame, a slide reciprocably mounted therein, an operating shaft, a driving connection between said shaft and said slide, a variable speed electric motor for operating said shaft at high speed and low speed, a plurality of switch controlling cams operable in timed relation with said shaft, a plurality of switches controlled by said cams, and means controlled by said switches for operating said motor at low speed during the work forming part of a cycle of press operations and at high speed throughout the greater part of the return movement of the slide.

6. In a drawing press, a frame, a blank holder and a drawing slide reciprocably mounted in said frame, toggle means for operating said blank holder, additional means for operating said drawing slide, a crank shaft rotatably mounted in said frame and operably connected to both said toggle means and additional means, to produce one complete cycle of blank holder and drawing slide movements for each revolution of said shaft, drive means for operating said crank shaft at high and low speeds, and means synchronized with said crank shaft for controlling the speed of said drive means to cause low speed operation of said crank shaft during the work forming part of a cycle of press operations and to cause high speed operation of said crank shaft for the return movement of the drawing slide.

ARTHUR A. BYERLEIN. 60
